UNITED STATES PATENT OFFICE.

EDGAR S. COMBS, OF ROCHESTER, NEW YORK, ASSIGNOR TO WILLIAM S. KING, OF MINNEAPOLIS, MINNESOTA.

LASTING-MACHINE.

SPECIFICATION forming part of Letters Patent No. 443,429, dated December 23, 1890.

Application filed December 24, 1889. Renewed October 17, 1890. Serial No. 368,390. (No model.)

To all whom it may concern:

Be it known that I, EDGAR S. COMBS, a citizen of the United States, residing at Rochester, in the county of Monroe and State of New York, have invented certain new and useful Improvements in Lasting-Machines, of which the following is a specification.

My invention relates to the jaws employed in lasting-machines to fold the edges of the upper over upon the last or insole; and it consists of a former, arranged to bear upon the ends of the fingers or blades of the jaw to bring them into conformity with the curvature of the last, the formers being exchangeable and removable, so that the same jaw may be quickly and accurately adjusted to work in connection with either right or left lasts at will.

In the drawings, Figure 1 is a perspective view of a pair of my improved lasting-jaws looking from the back; Fig. 2, a plan view, partly in section; Fig. 3, a sectional view on the line *xx*; Fig. 4, a view illustrating a slight modification; and Fig. 5 a view illustrating the construction of one of the fingers or blades.

A A' indicate the stock or body of the jaws, which are commonly employed in pairs, both jaws being of like construction and each mounted upon suitable supporting and actuating mechanism, which, however, constitutes no part of the present invention. Mounted in the stock or body of each jaw are blades or fingers B, against the outer ends of which bears the removable former C, each of the fingers being provided with a cylindrical stem *a*, which works through a conical hole *b*, formed in the wall of the jaw, as shown in Figs. 2 and 3. The length of the shanks or stems *a* varies, and it will be seen that when the bar or former *C* is removed and the fingers are pushed outward they will assume the position shown in Fig. 2 by the dotted lines. When the fingers are in this position, they are adapted to work on that part of the last corresponding to the outside of the shoe; but when the bar is applied some of the fingers will be pushed inward farther than the others, thereby presenting a working face corresponding to the curvature of the inside of the last E.

In working with "right" lasts the bar will not be used on the jaw A, (shown in the drawings,) but will be applied to the jaw A' on the opposite side of the machine; but when working with "left" lasts the bar will be removed from the companion jaw A' and applied to the jaw A in the manner above stated.

In order to hold the bar or former C in place, one end is inserted into an opening formed in a plate *c*, secured to the lower end of the jaw, while the opposite end is held in place by means of a latch *d*, hinged or pivoted to the upper end of the jaw. I do not wish to limit myself to any particular construction of former, nor to the means herein shown for securing said bar or former in position, as it is obvious that these matters may be varied considerably without departing from the spirit of my invention. The longitudinal movements of the fingers are limited in one direction by a shoulder *f*, formed upon the shank, and in the other direction by means of a head or enlargement *e*, formed upon or secured to the outer end of each finger, as shown.

By providing the jaw with the conical holes or openings *b* for the shanks of the fingers, the latter are permitted to yield in any direction and adjust themselves as required.

When the jaws are used on comparatively straight lasts, the blades or fingers will move nearly in the same plane than when the jaw is used on lasts having a greater curvature, and it will be apparent that when the fingers are in the straight plane they will occupy more space than when they are in the curved plane. To provide for this variation and to take up the space that would otherwise be found between the blades or fingers, I employ one or more set-screws *g*, which are designed to bear against the end finger, so as to crowd the fingers together. In other words, when curved lasts are used the screws will be turned inward to crowd the fingers together; but when straight lasts are used the screws will be drawn back to allow the fingers to straighten out. Each of the fingers is milled out or countersunk on its outer face, as at *h*, Figs. 1 and 5, so as to form a bearing *i* along both edges of the fingers immediately beneath the

former D, used to impart the desired curvature to the row of fingers. This former D may be of the construction shown in Gray's patent, No. 391,467, or of any other desired construction, and by bearing upon the backs of the fingers along both edges the fingers are prevented from tipping or rocking, as frequently happens under prior plans.

The end former C, instead of having a flat straight face to bear upon the ends of the fingers, may have a wavy or variable bearing-face, so as to cause some of the fingers to project farther than others in order that the jaw may be used in connection with special forms 15 of lasts, as shown in Fig. 4.

Having thus described my invention, what I claim is—

1. A lasting-machine jaw having a series of longitudinally-adjustable fingers or blades 20 and a removable former or bar adapted to bear and to be clamped against the ends of the fingers.

2. In a lasting machine, two jaws, each provided with a series of longitudinally-adjustable fingers, and a removable and changeable former or bar adapted to be applied to either 25

of the jaws at will and to bear against the ends of the fingers of the jaw to which it is applied.

3. In a lasting-machine jaw, the combination, with a body or stock provided with a series of conical holes b, of the fingers or blades having their shanks mounted in said holes. 30

4. In combination with the stock or body having the perforated lug c and hook or catch 35 d, fingers or blades, and a removable end former.

5. In a lasting-machine jaw, the combination, with a stock or body and a bar D, of the fingers countersunk on their outer faces to 40 form bearings i along their edges.

6. A lasting-machine jaw comprising a perforated stock or body, a series of fingers having shanks of different lengths, and a rigid bar adapted to be applied to the ends of the 45 fingers, substantially as shown and described.

In witness whereof I hereunto set my hand in the presence of two witnesses.

EDGAR S. COMBS.
